2 Sheets-Sheet 2

Fig. 2.

Fig. 3.

This technical drawing shows a mechanical assembly, likely a pump or valve, with various parts labeled with numbers. The assembly includes a central vertical rod, a horizontal plate, and several nuts and washers. Numbered callouts point to specific features: 35 points to the top of the vertical rod; 36 points to a nut on the left; 37 points to a nut on the right; 38 points to a washer; 39 points to a nut on the right side; 40 points to a washer; 41 points to a nut on the left side; 42 points to a washer; 43 points to a nut on the right side; 44 points to a washer; 45 points to a nut on the left side; 46 points to a washer; 47 points to a nut on the right side; 48 points to a washer; 49 points to a nut on the left side; 50 points to a washer; 51 points to a nut on the right side; 52 points to a washer; 53 points to a nut on the left side; 54 points to a washer; 55 points to a nut on the right side; 56 points to a washer; 57 points to a nut on the left side; 58 points to a washer; 59 points to a nut on the right side; and 60 points to a washer.

UNITED STATES PATENT OFFICE

HAROLD ARMITAGE, OF BROOKLINE, MASSACHUSETTS, ASSIGNOR TO UNIVERSAL WINDING COMPANY, OF BOSTON, MASSACHUSETTS, A CORPORATION OF MASSACHUSETTS

SUPPLY HOLDER

Application filed January 30, 1930. Serial No. 424,709.

This invention relates to supply-holders for holding cops, bobbins or other forms of packages of yarn, thread and the like to deliver the material to winding machines and other textile apparatus.

In the following specification and claims the terms "bobbin" is used generally to indicate any preferred form of supply, and the term "yarn" is employed in a broad sense to 10 designate all varieties of strand material.

One object of the invention is to provide a supply-holder which may be operated more conveniently and expeditiously to doff a spent bobbin and apply a fresh bobbin to 15 delivering position.

Another object of the invention is to provide a device of the type specified from which the spent or exhausted bobbin is automatically ejected by the action of applying a fresh 20 bobbin to position.

Another object of the invention is to provide a device of the type specified having a plurality of bobbin-supporting means and adapted to be manually rotated to bring a 25 fresh bobbin into delivering position while at the same time discharging a spent bobbin to cast it into a suitable receptacle placed therebelow.

Further objects of the improvement are set 30 forth in the following specification which describes a preferred form of construction of the invention, by way of example, as illustrated by the accompanying drawings.

In the drawings:

35 Fig. 1 is an end view of a conventional type of winding machine illustrating the present improved supply-holder as applied to use therewith;

Fig. 2 is an enlarged view showing the 40 supply-holder in its relation to the tension-device of the winding machine, and illustrating a nearly spent bobbin in delivering position thereon and a fresh bobbin in place to be substituted for the exhausted bobbin;

45 Fig. 3 is a transverse sectional view of the support or mounting for the supply-holder taken on line 3—3 of Fig. 2;

Fig. 4 is a plan view of the supply-holder and its support; and

50 Fig. 5 is a perspective view of the spring-

In general the present improved supply-holder comprises a rotatable element carrying a plurality of radially disposed spindles or other holding means for bobbins and adapted to be manually turned to bring a fresh bobbin into delivering position while at the same time releasing a spent bobbin therefrom.

Recent improvements in the textile art have greatly increased the speed of winding and other transfer processes, but little attention has been given to the manual operations required for tending the machines and supplying the apparatus with fresh material. As the speed of a winding machine or other apparatus is increased its rate of production is correspondingly augmented and, obviously, a greater loss of production is suffered 65 while the machine is stopped to replenish its supply. Economy in the time required for such operations is therefore a most important consideration and it is for this purpose that the present invention is designed to expedite 70 the doffing of the exhausted bobbins and the placing of fresh supplies in delivering position.

Referring to Fig. 1 of the drawings, 2 designates one of the legs or standards supporting a winding machine of the usual gang or multiple unit type, and 3 indicates the bed or frame on which the winding units are mounted. The winding mechanism as herein illustrated is of a well known type comprising a 80 drum or drive-roll 5 and a rotatable cop-holder or yarn-receiver 6 on which the package is wound. The cop-holder 6 is carried at the end of a swinging arm, indicated generally 85 at 7, which is pivoted at 8 to an upright 9, whereby the package may be supported in contact with the drive-roll 5 to adapt it to be driven therefrom with its axis receding from the roll as the winding increases in diameter. In the type of machine herein illustrated the 90 thread or yarn, indicated at 4, is traversed longitudinally of the cop-holder 6 by means of a reciprocating thread-guide 10. The 95 thread-guide 10 is mounted to slide on horizontal tracks or ways 11 and 12 and carries 100

a roller or bowl 13 engaging a helical groove 14 in the rotating cam 15 from which it is reciprocated. The construction of the winding mechanism as above indicated is well known to those versed in the present art and is therefore not herein illustrated in detail.

Each winding unit is usually provided with a tension-device for applying resistance or tension to the draft on the yarn as it feeds to the cop or package being wound, and the present drawings illustrate a disk-tension for this purpose. In Fig. 1 the tension-device is shown as mounted on a bracket 17 bolted to the front of the frame of the winding machine at 18 and having a horizontal shelf or rest 19 supporting a vertical spindle 20. A pair of opposite tension-disks 21 are mounted on the spindle 20 with a weight-holder 22 slidable on the spindle thereabove and carrying a suitable number of weights 23 which apply pressure to hold the tension-disks against the strand of yarn drawing therebetween. The weight-holder 22 is preferably arranged to bear against a spring 24 coiled around the spindle 20, whereby a yielding pressure is exerted on the upper tension-disk to press it down against the lower disk. The strand of yarn *y* is guided in an opening or guide-eye 26 at one side of the shelf 19 and draws across the top of the shelf to lead between the two tension-disks 21. From the tension-device the strand *y* draws through a suitable slab-catcher 27, as usually provided, and thence leads to the thread-guide 10 to be fed therefrom and traversed thereby on the cop or package being wound.

In delivering yarn or other strand material from cops, bobbins and other types of headless packages the strand is usually drawn off over the end of the package, the supplies being arranged below the winding-units with their axes in line with the point to which the yarn delivers as it feeds through the tension-device. In the present application of the invention a horizontal rod 28 is provided as a support for a plurality of supply-holders, the rod extending the length of the winding machine with its ends held in brackets 29 attached to the legs 2. As indicated in Figs. 1 and 2, the brackets 29 are fastened to the web of the legs 2 by means of clamps 30 secured in place by bolts 31, and the rod 28 is held in hubs 32 at the ends of the brackets by means of set-screws 33, see Fig. 4.

It will be understood that a supply-holder is provided for each winding unit and the construction and arrangement of the present improved device is as next described. The main element of the holder consists of a rotatable member constructed in the form of a hub or annulus 35 and provided with a plurality of circumferentially disposed bosses 36 drilled to receive the radial spindles 37. Preferably, the bosses 36 are tapered toward their outer ends to adapt them to enter the

enlarged end of the bores in the bobbin-tubes *b* to center the bobbins on the spindles. The circular hub or annulus 35 is rotatable on a bearing-member 40, see Fig. 3, secured fast on the horizontal rod 28. The member 40 is constructed with a hub 41 bored to receive the rod 28 and provided with a set-screw 42 for securing it fast in place thereon. A circular flange or plate 43 supported from the hub 41 is provided on its side with an overhanging annular rim 45 which forms the journal or bearing for the rotatable hub 35. A cap or disk 46 is fitted against the edge of the rim 45 to retain the hub 35 in place on its bearing, the disk being fastened to the side of the member 40 by means of screws 47 screwed into lugs or bosses 48 projecting from the side of the flange 43. Through the above described construction the hub or annulus 35 is mounted to rotate on the member 40 to bring the spindles 37 successively into vertical position with their axes alined with the guide-eye 26 to which the strand delivers as it feeds to the tension-device.

Means are provided for retaining the rotatable member or annulus 35 in fixed position after each rotative movement thereof. As herein shown this means consists of a detent-latch or pawl 50 which engages with suitable depressions or slots 51 in the side of the hub 35. As a preferred form of construction the pawl 50, shown in enlarged perspective view in Fig. 5, is constructed from a strip of spring metal bent into shape to adapt it to be hooked through an opening 53 in the side of the plate or disk 46. The opening 53 is in the form of an elongated slot which is interrupted by a cross-piece 54 formed by slitting the metal at the sides of the slot and bending it outwardly in the shape of a loop as shown most clearly in Fig. 4. The detent-latch 50 has a flat end 55 adapted to overlie the side of the disk 46, and beyond this portion it is bent into a square-sided loop 56 which passes under and around the cross-piece 54. Beyond the loop 56 the latch is inclined inwardly in a length 57 having its end bent around in a toe-piece 58 adapted to engage with the V-shaped grooves or slots 51 which provide ratchet-teeth or stops on the side of the rotatable hub 35. Through the engagement of the toe 58 of the pawl 50 with the grooves 51 the hub 35 is restrained from unwarranted or accidental turning movement, but when it is required to rotate the hub to bring a fresh bobbin into delivering position the pawl yields readily and rides along the face of the hub until it engages the next succeeding groove.

The method of operation of the complete device is as next explained: Assuming that a bobbin *B* is in place on the uppermost spindle 37 with its axis alined with the guide-eye 26 through which the strand *y* feeds, as the winding machine is operated the material is

drawn off from the bobbin and wound onto the cop-holder 6 to build the desired form of package.

As the winding proceeds and the supply of 5 yarn on the delivering bobbin becomes depleted the operator places a fresh bobbin on the next forward spindle 37, just before the end runs out on the first bobbin. As the last few coils of yarn are pulling off from the 10 delivering bobbin the operator shifts the fresh bobbin B into delivering position by turning the supply-holder hub 35 on its bearing 45. As the hub 35 is rotated the pawl 50 rides out from the notch or groove 51 with 15 which it is engaged and springs into the next notch just as the new bobbin is brought into vertical position. The complete operation of placing the fresh bobbin on its spindle and adjusting it to delivering position may be 20 effected by a single manual movement, the operator impaling the bobbin on the spindle and pushing it upwardly with a circular motion of the hand. Meanwhile, the operation of the winding machine is arrested by the ac- 25 tivation of its automatic stopping-device as usually provided, and the operator has only to tie up the end of the fresh bobbin with the trailing end from the package, the spliced yarn being then drawn into the tension-device 30 and slub-catcher by the automatic threading action of these devices.

The operation of placing a fresh bobbin on the holder and adjusting it to delivering position as the end runs out on the spent bobbin is repeated as becomes necessary during the winding operation, and with the present improved device very little time is required for resupplying the machine with yarn.

Each time a new bobbin is applied to the 40 holder and turned into delivering position the empty bobbin-tube or yarn-carrier b is carried over to the right, as viewed in Fig. 2, and finally as it is turned into position with its spindle inclined downwardly, as 45 represented by the dash lines in Fig. 1, the empty tube b will drop off from the holder to be cast into a suitable receptacle or bobbin-box 60 which may rest on the floor at the front of the machine. As a consequence of 50 the automatic doffing of the spent bobbin and the simple method of applying a fresh one in its place, the interval during which the winding is arrested is very brief and therefore the loss of production is materially reduced as compared with the usual method where 55 an exhausted bobbin must be first removed and a fresh bobbin placed on the same spindle.

While the device is herein described and 60 illustrated as embodied in a preferred form of construction, the structure and arrangement of its parts may be varied at will without departing from the spirit or scope of the invention. Moreover, the improved device is susceptible of various uses in transfer proc-

esses other than that herein described, and the invention is therefore not limited as to its method of application.

What I claim is:

1. A supply-holder comprising a plurality of means each adapted to hold a bobbin, means for mounting said holder to rotate on a horizontal axis to adapt it to be adjusted to bring the bobbins successively into delivering position, and automatically-operated detent-means for retaining the holder in the position to which it is adjusted. 70

2. A supply-holder comprising a member journaled to rotate on a horizontal axis, a plurality of spindles disposed radially of said member and adapted to receive yarn supplies, and automatically-operated detent-means for maintaining said rotatable member in adjusted relationship with a bobbin on one of the spindles in delivering position. 80

3. In a device of the type specified, the combination of a member pivoted to rotate on a horizontal axis, means on said member for supporting bobbins, and resiliently-operated detent-means for restraining said member from rotation while allowing it to be manually turned to successively bring the bobbins into delivering position. 90

4. In a device of the type specified, the combination of a bearing, a member rotatable on a horizontal axis on the bearing and provided with a plurality of radially disposed means for supporting bobbins, and automatically-operated detent-means for maintaining the rotatable member in fixed relationship while adapting it to be turned to successively bring the bobbins into delivering position. 100

5. In a device of the type specified, the combination of a bearing, a member rotatable on a horizontal axis on the bearing and provided with means for supporting bobbins disposed radially of its axis, a resilient latch, and detent-means on the rotatable member adapted to be engaged by the latch to retain said member in the position to which it is adjusted. 110

6. In a device of the type specified, the combination of a flanged bearing, an annulus rotatable on the bearing and having detent-notches in its side, spindles projecting radially from the annulus to adapt them to support bobbins, and a latch on the bearing engageable with the notches in the annulus to hold the latter in its adjusted position. 115

7. In a device of the type specified, the combination of a flanged bearing, an annulus rotatable on said bearing and provided with notches in its side, spindles projecting radially from the annulus, a plate for maintaining the annulus in place on its bearing, and a latch on the plate adapted to engage the notches in the annulus to retain the latter in adjusted position on its bearing. 120

8. In a device of the type specified, the combination of a member having a flanged 130

bearing, an annulus rotatable on said bearing, a plate secured to the bearing abutting the side of the annulus to hold it in place, said plate formed with a slot with a bar extending thereacross, and a latch hooked onto the cross-bar and projecting through the slot in the plate with its end adapted to yieldingly engage the notches in the side of the annulus.

In testimony whereof, I hereunto affix my
10 signature.

HAROLD ARMITAGE.
